TETHERED BALL BOWLING GAME BOARD

Walter Moe, Huntington, N.Y., assignor to Aurora Products Corp., West Hempstead, N.Y.

Filed Apr. 4, 1972, Ser. No. 241,105

Term of patent 14 years

Int. Cl. D21—01

U.S. Cl. D34—5 BB

FIG. 1.

FIG. 2.

FIG. 3.

FIG. 1 is a plan view of a tethered ball bowling game board of the present invention;

FIG. 2 is a right side elevation view thereof; and FIG. 3 is a front elevation view thereof.

I claim:

The ornamental design for a tethered ball bowling game board, substantially as shown and described.
